US00D864679S

(12) **United States Design Patent** (10) **Patent No.:** **US D864,679 S**
Goodwin et al. (45) **Date of Patent:** **** Oct. 29, 2019**

(54) **APPLICATOR**

(71) Applicant: **OMS Investments, Inc.**, Los Angeles, CA (US)

(72) Inventors: **Randy M. Goodwin**, Grove City, OH (US); **Paul Havlovitz**, Dublin, OH (US); **Ryan R. Berger**, Columbus, OH (US); **Paul Hsu**, Lewis Center, OH (US); **Michael T. Kopczewski**, Grove City, OH (US); **Timothy Michael Martin**, Westerville, OH (US); **Jay F. Perkins**, Pickerington, OH (US)

(73) Assignee: **OMS Investments, Inc.**, Los Angeles, CA (US)

(**) Term: **15 Years**

(21) Appl. No.: **29/674,494**

(22) Filed: **Dec. 21, 2018**

CPC B05B 7/2421; B05B 9/01; B05B 1/00; E03C 1/046; A01G 25/023

CLAIM

The ornamental design for an applicator, as shown and described.

DESCRIPTION

FIG. 1 is a perspective view of an applicator; FIG. 2 is a front elevation view thereof; FIG. 3 is a rear elevation view thereof; FIG. 4 is a side elevation view thereof; FIG. 5 is an opposite side elevation view thereof; FIG. 6 is a top plan view thereof; and, FIG. 7 is a bottom plan view thereof.

The broken line showings of the applicator are included for the purpose of illustrating portions of the article and form no part of the claimed design.

1 Claim, 6 Drawing Sheets
